UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

STEEPLE CLOSURE FOR INK BOTTLES

Application filed February 20, 1928. Serial No. 255,624.

My invention relates to stoppers for ink bottles and the like adapted to carry a quill or equivalent member.

Heretofore in the construction of ink bottles adapted to hold india ink or the like, the closures have comprised a stopper having a substantially steeple-like contour of moldable material provided with a depending tubular sleeve upon which a cork sleeve was concentrically arranged and within which tubular sleeve the quill was mounted. In these prior constructions, the cork fitted into the open neck of the bottle to seal the same but such prior constructions possessed certain disadvantages. For instance, in order to get the last drop of ink out of the bottle it was necessary to press down upon the stopper so far that it was hard to dislodge the cork from the neck of the bottle and furthermore, the cork got full of ink and it in time became corroded. In addition, in opening the bottle, due to the frictional contact of the somewhat resilient cork with the neck of the bottle, such a firm grip was provided that when the cork was pulled out, the reactive force tended to spill the ink from the bottle.

The objects of my present invention are to provide a new type of quill carrying stopper for an ink bottle wherein the construction permits the stopper to be withdrawn from the bottle without spilling the ink and wherein the quill is carried by the stopper at a uniform height in spaced apart relation from the bottom of the bottle and within the same, and wherein the stopper is constructed so that when removed from the bottle and laid upon a flat surface it will remain stationary with the quill out of contact with the flat surface; still another object of my invention resides in providing a novel stopper of the character described wherein the steeple-like portion of the stopper is molded around and in permanent connection with a screw cap and wherein the screw cap is arranged so that an integral portion of the molded steeple projects through the top of the cap and forms a permanent mounting for the quill; still another object of my invention resides in providing a stopper of the

above character wherein a screw cap is constructed and arranged to carry the quill and wherein the screw cap itself is formed with a seat or abutment to receive the end of the quill and wherein the screw cap itself is provided with an integral portion directly gripping the quill or is provided with a separable portion adapted to grip the quill and is permanently held connected to the screw cap, and all of these constructions embody a further inclusion of a washer-like element of cork held within the under face of the screw cap so as yieldably to engage the upper edge of the mouth of the bottle when the screw cap grips the threads or engaging projections on the neck of the bottle, the cork will be forced into seating engagement with the mouth of the bottle; still another object of my invention resides in the provision of an angularly sided steeple portion and alternatively in the construction of a stopper having a flat top and upon which it may rest whereby in both constructions the closure may remain stationary on a flat surface with the quill held in spaced relation from the flat surface; another object of my invention is to provide a modified construction wherein the inside face of the sheet metal screw cap has an independent member of yieldable material attached thereto, which member has an outer peripheral portion providing a sealing washer or element and an inner substantially central portion which is constructed to provide a mounting for the quill or other instrument carried by the cap.

These and other objects of my invention will be apparent from a perusal of the following specification taken in connection with the accompanying drawings, wherein:

Figure 1 is a perspective view of my preferred form of steeple shaped stopper for an india ink bottle;

Figure 2 is a cross sectional view of the stopper and the upper portion of the bottle neck;

Figure 3 is a section taken at right angles to Figure 2; and

Figure 4 is a section on line 4-4 of Figure 2.

Referring now to my invention in general, in the form shown in Figs. 1, 2, and 3, it comprises a screw cap carrying thread engaging or abutment engaging lugs which are adapted to grip cooperative portions on the neck of the bottle for holding or permitting the release of the stopper from the bottle by a rotational movement of the stopper as distinguished from a pulling-out movement as heretofore used in the art. In addition, the stopper comprises a preferably steeple-like molded portion which is molded to the outer face of the screw cap so as to constitute a turning member and this moldable material has an integral portion passing through a central opening in the top of the screw cap whereby to provide a depending sleeve, the hollow portion thereof forming a relatively long seat for the reception and mounting of the quill therein. In addition, this depending sleeve constitutes a mounting for a cork washer which is snugly held within the screw cap, being held in place by a frictional grip of this cork washer against the inner walls of the cap and also by tight engagement with the integral and depending molded sleeve. The outer surface of the steeple-like portion is preferably formed with angularly shaped sides so that when the steeple-like stopper is laid upon a flat surface such as a desk or table, the quill will be held in raised position from the surface of the desk and due to the flat sides, the steeple-like stopper will not roll as heretofore.

Referring now to the drawings in detail, I prefer to illustrate my invention in connection with the usual type of ink bottle for holding India ink such as used by draftsmen and the like. This bottle 2 is formed on its neck 4 with the usual glass screw threads 6 which may be of any type either of the continuous threads or mutilated threads or spaced apart lugs. It must be understood that the shape of the bottle and the arrangement of the threads except in so far as they cooperate with my novel type of stopper constitute no part of my invention.

In the form shown in Figures 1, 2, 3, and 4, my invention comprises a sheet metal screw cap comprising the usual depending peripheral flange 8 which is formed at appropriately spaced portions with inwardly projecting locking ears or lugs 10 adapted to engage under the threads 6 on the neck of the bottle as is well known in the art. The upper or top surface 12 of this screw cap is provided with an opening 14 through its central axis. The stopper also includes a steeple or other ornamental turning portion 16 of suitable moldable material such as hard rubber, bakelite, or other synthetic moldable material. This steeple is molded so as to be arranged to cover the peripheral flange portion 8 and this molded portion 18 of the steeple is provided with angularly dis-

posed sides. In this instance, it is shown as hexa-sided. In addition, this steeple projects upwardly forming a substantially rounded or a blunt steeple-like portion which on its upper end is also provided with angular sides 20. The steeple is also provided with a depending sleeve-like projection 22 formed integrally therewith and passing through the opening 14 in the sheet metal top portion 12 of the cap. This sleeve is hollow within for a great portion of its length so as to form a seat for snugly receiving the quill 24. Thus the quill is firmly gripped and held in position within this sleeve 22 of the steeple. In addition, the stopper is provided with a cork washer 26, the inner wall of which frictionally grips the outer wall of the sleeve 22 and the outer periphery of which is adapted snugly to grip the inner wall of the peripheral flange 8 of the screw cap whereby to hold the cork washer in position within the under side of the screw cap so that when the stopper is placed upon the open neck of the bottle and the locking lugs 10 engage under the threads or locking abutments on the neck of the bottle, the stopper will be forced down so that the cork washer 26 will seal the open end or mouth of the bottle and in this position the bottom portion of the quill 24 will be held at a definite position and slightly spaced away from the inner bottom wall of the bottle.

Thus it will be seen that by a slight rotation of the steeple 16 the cap molded thereto will be rotated so as to release the stopper from the bottle and without spilling or distributing the ink or other liquid within the bottle. It will also be seen that by reason of my construction, there is no cork sleeve to be corroded nor to be wedged within the mouth of the bottle so that the stopper and the quill are always at a definite position in closed engagement with relation to the mouth and the bottom of the bottle. It will further be evident that by reason of the angular sides on the exterior faces of the flange portion 18 of the steeple and the upper portion 20 of the steeple, the steeple when laid upon a flat surface such as a desk will remain stationary and will not roll and the quill will be held in raised position. Any type of means may be used for firmly and permanently holding the quill within the tubular sleeve 22. The mounting may be either by frictional grip or any type of adhesive may be used for accomplishing this. I prefer to use a mere frictional grip between the surfaces of the quill and the inner wall of the sleeve 22, it being manifest that the upper end 28 of this hollow cavity within the projection 22 forms a firm abutment or seat for the end of the quill to position it.

It is thought that, from the foregoing description, it will be apparent that I have

provided a very advanced construction for quill carrying stoppers for india ink bottles and the like.

While I preferably construct my stopper to carry quills by reason of the frictional gripping engagement with the sleeve-like projections and whereby the quills may be freely removed for detachment or replacement, I wish it to be understood that other similar tools or devices may be inserted and used in lieu of the quills. It will be seen that by reason of this construction, great facility in opening and closing and using the india ink bottle is afforded and especially in relation to the placing of the stopper upon the desk when once opened since the stopper will not roll about. Furthermore, by using the moldable material in the manner shown in Figure 1 of the drawing, I am enabled to utilize this moldable material not only for the purpose of providing a good gripping engagement to turn the screw cap and to provide an ornamental surface for the screw cap but am also enabled to provide a construction whereby the cork washer which overlies the mouth of the bottle will be held permanently in position between the inward depending sleeve of the molded material and the inner surface of the screw cap while at the same time providing a firm yet detachable mounting for the quill.

Having thus described my invention what I claim as new and desire to protect by Letters Patent is:

1. A stopper construction for India ink bottles comprising a sheet metal screw cap provided with a peripheral flange and a top, said flange having locking means for engaging locking projections on the neck of the bottle and said top of the cap, having an opening therethrough, a steeple-like member of moldable material molded about the exterior surface of the cap and having an integral inwardly projecting sleeve passing through the opening in the top of the cap, a quill fitting said sleeve and a sealing washer surrounding and gripping the sleeve and lying within the top surface of the cap whereby when the cap is screwed upon the neck of the bottle, said sealing washer will sealingly engage the open mouth of the bottle.

2. A stopper construction for india ink bottles including a sheet metal screw cap provided with a peripheral flange and a top, said flange having locking means for engaging locking projections on the neck of the bottle, means mounted on the under surface of the top of said screw cap for securing a quill in position to depend through the neck of the bottle, and means for sealing the top surface of the neck of the bottle when said cap is in position and a steeple-like sheath molded upon the outer surfaces

of the cap and having a portion encircling the flange thereof.

3. In a device of the class described, the combination of a sheet metal screw cap including a depending peripheral flange formed to interlockingly engage external surfaces of a bottle neck, a covering of moldable material formed about said cap and encircling the flange thereof and means forming a quill seat depending from the under side of the screw cap, a compressible washer disposed on the under side of the screw cap and held in centered position by the first named means.

4. In a device of the class described, in combination a bottle having a neck and a stopper for the bottle including a steeple like portion of moldable material formed with a depending peripheral flange and means carried within the flange for interlockingly engaging the neck of the bottle.

5. In a device of the class described, in combination a bottle having a neck and a stopper for the bottle including a steeple like portion of moldable material formed with a depending peripheral flange and means carried within the flange for interlockingly engaging the neck of the bottle, said means comprising a sheet metal screw cap having a peripheral flange engaging within the depending flange of said steeple like member.

6. In a stopper construction for ink bottles and the like, a screw cap having a depending peripheral flange provided with locking means for engaging co-operative locking means on the neck of the bottle, said screw cap having a covering of moldable material formed to the outer surfaces of the cap, said covering having an integral depending portion forming a sleeve extending centrally through the top of the cap, said sleeve being formed to receive a device for applying the contents of the bottle.

7. In a device of the class described, the combination of a screw cap having a depending peripheral flange configurated to provide locking projections for engaging co-operating projections formed in the external surfaces of a bottle neck and a sheath of molding material covering the exterior surface of said screw cap, said sheath being molded thereto and having a central upstanding steeple-like portion, whereby to facilitate manipulation of said screw cap, said sheath having a central sleeve like portion extending downwardly through the screw cap and a quill carried by said sleeve-like portion.

8. A stopper construction for india ink bottles, including a steeple-like member of moldable material formed with a depending peripheral flange, a metallic shell forming a cap provided with a central opening secured within the flange and formed with locking

- projections extending inwardly for engaging locking projections on the neck of the bottle, said moldable material being formed with a central portion extending concentrically downwardly through the opening of the cap and formed to provide a quill mounting.
9. A stopper construction for india ink bottles, including a steeple-like member of moldable material formed with a depending peripheral flange, a metallic shell forming a cap provided with a central opening secured within the flange and formed with locking projections extending inwardly for engaging locking projections on the neck of the bottle, said moldable material being formed with a central portion extending concentrically downwardly through the opening of the cap and formed to provide a quill mounting, and an annular washer of compressible material disposed in the cap around the quill mounting for the purpose of sealing the bottle opening when the cap is applied in place on the bottle.
10. A stopper construction for india ink bottles including a sheet metal screw cap provided with a peripheral depending flange and a top having a central opening, said flange having locking means for interlockingly engaging the neck of the bottle and a molded quill carrying member having a portion encircling and securing the outer surfaces of the screw cap including the depending portion thereof, said quill carrying member being formed to provide an upwardly extending steeple like formation whereby to facilitate manipulation of the closure and having an integral molded portion extending downwardly through the central opening of the cap and projecting from the underside thereof, said depending portion comprising a sleeve located axially of the screw cap and adapted to have an ink applying quill seated thereto.
- 45 In witness whereof, I have hereunto subscribed my name.

ADOLPH LANGSNER.
